UNITED STATES PATENT OFFICE.

HUGH W. SANFORD, OF KNOXVILLE, TENNESSEE.

RAILWAY CAR.

Application filed August 31, 1923. Serial No. 660,416.

To all whom it may concern:

Be it known that I, HUGH W. SANFORD, a citizen of the United States, residing at Knoxville, in the county of Knox and State of Tennessee, have invented a new and useful Improvement in Railway Cars, of which the following is a specification, reference being had to the accompanying drawing.

My invention relates particularly to mine 10 cars and other cars of any type wherein the frame of the car has side sills and end sills connecting the side sills.

The chief object of the invention is to produce a strong and durable end sill in which 15 there is a limited amount of metal. Heretofore similar end sills have been made of cast metal. Effort to provide the necessary strength has led to putting into these structures an objectionably large amount of metal 20 and making the sill too expensive, and yet those sills have been unreliable on account of blow holes and other imperfections and shrinkage strains in the castings. A secondary object of the invention is to provide 25 a top draw bar piece that will not bend up or down under haulage strains.

The present invention involves the use of 30 rolled steel plate, preferably in a single piece, of great toughness and strength relative to weight, to form the principal member of the end sill. In the preferred form my improved end sill is composite, a second 35 or inner member composed of wood being added to a steel plate member. In another form, the second member is a casting.

My improved end sill is in form to also serve as a bumper and as a draw bar.

In the accompanying drawings,

Fig. 1 is a plan of a structure embodying 40 my improvement;

Fig. 2 is an elevation looking at the structure of Fig. 1 from the right;

Fig. 3 is an elevation looking at the structure of Fig. 2 from the left;

Fig. 4 is a plan showing a sheet steel blank from which is made the body of the end sill;

Fig. 5 is a perspective of said end sill detached from other parts;

Fig. 6 is a perspective of one of the corner members used for joining the side sills to the end sill;

Fig. 7 is an upright section on the line, 7-7, of Fig. 1, looking in the direction of 55 the arrows;

Fig. 8 is a horizontal section on the line, 8-8, of Fig. 2;

Fig. 9 is an upright section on the line, 9-9, of Fig. 1, looking in the direction of the arrows;

Fig. 10 is an upright section on the line, 10-10, of Figs. 1, 2 and 12, looking in the direction of the arrows;

Fig. 11 is an upright section on the line, 11-11, of Fig. 1, looking in the direction of 65 the arrows;

Fig. 12 is a horizontal section on the line, 12-12, of Fig. 2;

Fig. 13 is a horizontal section on the line, 13-13, of Fig. 2;

Fig. 14 is a perspective of the end sill bumper member;

Fig. 15 is a perspective of an anchor plate located at the middle and rear of the end sill;

Fig. 16 is a plan of an end sill in which the inner member is a casting, parts being broken away;

Fig. 17 is a side elevation, looking toward the right of the structure as shown in 60 Fig. 16;

Fig. 18 is a front elevation of the structure as shown by Fig. 16;

Referring first to Figs. 1 to 15, of the drawings, A A are the side sills. In the 65 form shown in the drawings these sills are of channel-form with flanges, A¹, directed outward.

B is the steel plate member of the end sill. This is of channel form and has the 90 upright web, B¹, (presenting a flat back face) and an upper horizontal flange, B², and a lower horizontal flange, B³. The corners of the flange B², are cut to make slanting edges, B⁴; and the corners of the lower flange, B³, are similarly cut to make slanting edges, B⁵. (Fig. 5). This member, B, is formed by folding the blank of Fig. 4 along the dotted lines, B⁶. The blank of Fig. 4 is cut from a plate of rolled 100 steel of desired thickness. This member, B, is also provided with holes, as will be described further on.

In the form shown in the drawings, the plate member, B, is long enough to partially 105 over-lap the adjacent ends of the side sills. Said member and the side sills are joined to each other by means of corner angle members, C. One of these angle members is shown in perspective in Fig. 6. One arm 110

or blade of the angle member rests against the outer flat face of the plate member, B, and is secured to the plate member by bolts or rivets, C¹, extending through said blade 5 and the plate member, B. The drawings show six such bolts or rivets. The other arm or blade of the angle member extends into the space between the flanges, A¹, of the adjacent side sill and bears against 10 the upright web of the side sill. Bolts or rivets, C², extend through said blade and said web to join said parts to each other. In the form shown in the drawings, six such bolts or rivets, C², are used. These 15 corner angle members and the bolts or rivets used for securing these angle members to the plate member, B, and the side sills, A, are to be sufficiently strong to give rigidity to the frame. The web, B¹, of the plate 20 member, B, is wider than the height of the side sills, A, to allow making a coupling link space, as will be described further on.

An inner or second member, D, of strong wood, preferably oak, is placed on the lower 25 flange, B³, and against the upright web, B¹, of the plate member, B. The upper and the lower and the inner face of the inner wood member, D, are straight; while the outward face of the wood member nearly conforms to 30 the outer edges of the flanges, B² and B³, of the plate member, B, the wood member being extended outward a little beyond said flanges.

Midway between the ends of the end sill 35 an angle-form anchor plate, D¹, extends across the upper face of the wood member, D, and between said member and the web, B¹, of the plate member, B, and is secured to said web by rivets, D², (Figs. 15, 12 and 40 13). The horizontal part of the anchor member has a hole, D³, to receive the bolt to be described further on. A bumper member, E, is curved and of channel-form, having an upright web, E¹, and an upper flange, E², and a lower flange, E³. Said bumper member is placed at the middle of the end sill and has its web, E¹, bearing against the outer, upright face of the wood member, D, while its upper flange, E², rests on the 45 upper face of the wood member, D, and its lower flange, E³, extends across the lower face of the flange, B³, of the plate member, B. This bumper member is to receive contact or impact from the bumper of another 50 car. The bumper member and the outer part of the wood member form a bumper, the wood being a cushioning member or material against which the bumper member rests.

55 Thus a coupling link space is left between the upper face of the wood member, D, and the upper flange of the bumper member on the one hand and the upper flange, B², of the plate member, B. Upright binding bolts, E⁴, extend through the bumper mem-

ber and the flange, B³, and the wood member, D, and the upper flange, B². Between the bumper member and the upper flange, B², each of said bolts is surrounded by a spacing sleeve, E⁵, whereby the distance between the bumper member and the flange, B², is maintained. Between the bolts, E⁴, and on the middle, longitudinal line of the car is the upright coupling bolt, F, extending through the two flanges of the bumper member, E, and the wood member, D, and the hole in the horizontal part of the anchor member, D¹, and through the upper flange, B², of the plate member, B. Between the upper flange, B², and the flange, E¹, the bolt, F, is surrounded by a spacing sleeve, F¹, which maintains the distance between said flanges. A coupling link, F², surrounds the bolt, F, and the spacing sleeve, F¹.

50 Between the bumper member, E, and the ends of the end sill, bolts, G, extend through the lower flange, B³, and the wood member, D, and the upper flange, B². Between the wood member and the web, B¹, each of said bolts is surrounded by a spacing sleeve, G¹, 55 and between each such spacing sleeve and the wood member is a washer, G².

55 By means of the various bolts and spacing sleeves and washers, the several members are firmly bound to each other to form the composite end sill. Tests have shown that while the weight of this end sill is not objectionable, it is amply strong, and it may safely be assumed that any number of these 60 sills sent to the trade will be free from such defects as will cause them to break.

65 It is to be observed that this composite end sill includes a bumper and a draw-bar structure, the upper flange, B², and the lower flange, B³, performing draw-bar function.

In the form shown by Figs. 16, 17 and 18, the second member is composed of a casting which is adapted to receive a spring-controlled draw bar.

70 This inner casting, H, is of a length approximately equalling the length of the steel plate member, B, and of a height to fill the space between the flanges, B² and B³, of the plate, B. On the middle longitudinal line of the car, the casting, H, has in its upper face a longitudinal channel, H¹, of suitable form to receive a spring-controlled draw bar, not shown. In the bottom of the channel, H¹, are an outer opening, H², and an inner opening, H³, which may receive members associated with the draw bar. Bolts, H⁴, extend through the flanges, B² and B³, and through the casting, H, and bind said members firmly to each other. In 75 this case, the draw bar and the casting, H, projecting outward beyond the flanges, B² and B³, take impact from another car.

80 By placing the steel plate member, B, against the face of the angle members, A, the height of the bumper may be fixed to 85

suit the height of bumpers on other cars with which the new car is to be used. In applying the plate member, B, to the new car, the member, B, being wider than the angle members, A, may be set at the desired height for riveting to the angle members.

The wooden inner member, D, combines elasticity with strength. Such elasticity limits the effect of impact.

10 I claim as my invention,

1. In a railway-car, the combination with side sills and corner pieces, of a plate metal end sill member formed to present a continuous and upright back face to the corner members and to present upper and lower horizontal flanges free from each other and extending from end to end of the sill and directed away from the car frame, substantially as described.

20 2. A composite end sill for railway-cars, said sill comprising a plate metal channel member formed to present an upright back face and to present upper and lower horizontal flanges directed away from the car frame, and a filling member between said flanges, substantially as described.

30 3. A composite end sill for railway-cars, said sill comprising a plate metal channel member formed to present an upright back face and to present upper and lower horizontal flanges directed away from the car frame, and a filling member located between and reaching outward beyond said flanges, substantially as described.

35 4. A composite end sill for railway-cars, said sill comprising a plate metal channel member formed to present an upright back face and to present upper and lower horizontal flanges directed away from the car frame, and a wood filling member between said flanges, substantially as described.

40 5. A composite end sill for railway-cars, said sill comprising a plate metal channel member formed to present an upright back face and to present upper and lower horizontal flanges directed away from the car frame, and a wood filling member located between and reaching outward beyond said flanges, substantially as described.

45 50 6. A composite end sill for railway-cars, said sill comprising a plate metal channel member formed to present an upright back face and to present upper and lower horizontal flanges directed away from the car frame, a filling member located between and reaching outward beyond said flanges, and a metal bumper member extending across said filling member, substantially as described.

60 65 7. A composite end sill for railway-cars, said sill comprising a plate metal channel member formed to present an upright back face and to present upper and lower horizontal flanges directed away from the car frame, a wood filling member located between and extending outward beyond said

flanges, and a metal bumper member extending across the wood filling member, substantially as described.

8. A composite end sill for railway-cars, said sill comprising a plate metal channel member formed to present an upright back face and to present upper and lower horizontal flanges directed away from the car frame, a filling member located between said flanges, and a metal bumper member extending across the filling member, substantially as described.

9. A composite end sill for railway-cars, said sill comprising a plate metal channel member formed to present an upright back face and to present upper and lower horizontal flanges directed away from the car frame, a filling member located between said flanges, and a metal bumper member extending across the filling member and one of said flanges, substantially as described.

10. A composite end sill for railway-cars, said sill comprising a plate metal channel member formed to present an upright back face and to present upper and lower horizontal flanges directed away from the car frame, a filling member located between said flanges with a link space between the upper flange and said filling member, and a coupling bolt extending through said flanges and filling member, substantially as described.

11. A composite end sill for railway-cars, said sill comprising a plate metal channel member formed to present an upright back face and to present upper and lower horizontal flanges directed away from the car frame, a filling member located between and reaching outward beyond said flanges with a link space between the upper flange and said filling member, and a coupling bolt extending through said flanges and filling member, substantially as described.

110 12. A composite end sill for railway-cars, said sill comprising a plate metal channel member formed to present an upright back face and to present upper and lower horizontal flanges directed away from the car frame, a filling member located between said flanges with a link space between the upper flange and said filling member, a coupling bolt extending through said flanges and filling member, and a metal bumper member extending across the filling member, substantially as described.

115 120 13. A composite end sill for railway-cars, said sill comprising a plate metal channel member formed to present an upright back face and to present upper and lower horizontal flanges directed away from the car frame, and a filling member of cushioning material located between and reaching outward beyond said flanges, substantially as described.

125 130 14. A composite end sill for railway-cars,

said sill comprising a plate metal channel member formed to present an upright back face and to present upper and lower horizontal flanges directed away from the car frame, a filling member of cushioning material, and a metal bumper member extending across said filling member, substantially as described.

15. A composite end sill for railway-cars, 10 said sill comprising a plate metal channel member formed to present an upright back face and to present upper and lower horizontal flanges directed away from the car frame, a filling member of cushioning material reaching outward beyond said flanges, 15 and a metal bumper member extending across said filling member, substantially as described.

16. A composite end sill for railway-cars, 20 said sill comprising a plate metal channel member formed to present an upright back face and to present upper and lower horizontal flanges directed away from the car frame, a filling member of cushioning material located between said flanges, and a metal bumper member extending across the filling member and one of said flanges, substantially as described.

17. A composite end sill for railway-cars, 30 said sill comprising a plate metal channel member formed to present an upright back face and to present upper and lower horizontal flanges directed away from the car frame, an anchor member placed between 35 said flanges and secured to the upright web of the channel member with a link space between the anchor member and the upper flange, and a filling member between the anchor member and the lower flange, substantially as described.

18. A composite end sill for railway-cars, 40 said sill comprising a plate metal channel member formed to present an upright back face and to present upper and lower horizontal flanges directed away from the car frame, an anchor member placed between 45 said flanges and secured to the upright web of the channel member with a link space between the anchor member and the upper flange, a filling member between the anchor member and the lower flange, and a metal bumper member, substantially as described.

19. A composite end sill for railway-cars, 50 said sill comprising a plate metal channel member formed to present an upright back face and to present upper and lower horizontal flanges directed away from the car frame, an anchor member placed between 55 said flanges and secured to the upright web of the channel member with a link space between the anchor member and the upper flange, a filling member between the anchor member and the lower flange, and a metal bumper member extending across said filling mem-

ber and said anchor member, substantially 65 as described.

20. A composite end sill for railway-cars, 70 said sill comprising a plate metal channel member formed to present an upright back face and to present upper and lower horizontal flanges directed away from the car frame, an anchor member placed between 75 said flanges and secured to the upright web of the channel member with a link space between the anchor member and the upper flange, a filling member between the anchor member and the lower flange, a metal bumper member extending across said anchor member and said filling member and the lower flange, substantially as described. 80

21. A composite end sill for railway-cars, 85 said sill comprising a plate metal channel member formed to present an upright back face and to present upper and lower horizontal flanges directed away from the car frame, an anchor member placed between 90 said flanges and secured to the upright web of the channel member with a link space between the anchor member and the upper flange, a filling member between the anchor member and the lower flange, and a coupling member extending through said flanges, anchor member, and filling member, substantially as described.

22. A composite end sill for railway-cars, 95 said sill comprising a plate metal channel member formed to present an upright back face and to present upper and lower horizontal flanges directed away from the car frame, an anchor member placed between 100 said flanges and secured to the upright web of the channel member with a link space between the anchor member and the upper flange, a filling member between the anchor member and the lower flange, a metal bumper member, and a coupling member extending through said flanges, anchor member, and filling member, substantially as described. 105

23. A composite end sill for railway-cars, 110 said sill comprising a plate metal channel member formed to present an upright back face and to present upper and lower horizontal flanges directed away from the car frame, an anchor member placed between 115 said flanges and secured to the upright web of the channel member with a link space between the anchor member and the upper flange, a filling member between the anchor member and the lower flange, a metal bumper member extending across said filling member and said anchor member, and a coupling member extending through said flanges, anchor member, and filling member, substantially as described. 120

24. A composite end sill for railway-cars, 125 said sill comprising a plate metal channel member formed to present an upright back

- face and to present upper and lower horizontal flanges directed away from the car frame, an anchor member placed between said flanges and secured to the upright web 5 of the channel member with a link space between the anchor member and the upper flange, a filling member between the anchor member and the lower flange, a metal bumper member, and a coupling member 10 extending through said flanges, anchor member, and filling member and said bumper member, substantially as described.
25. A composite end sill for railway-cars, said sill comprising a plate metal channel member formed to present an upright back face and to present upper and lower horizontal flanges directed away from the car frame, an anchor member placed between said flanges and secured to the upright web 15 20 of the channel member with a link space between the anchor member and the upper flange, a filling member between the anchor member and the lower flange, a metal bumper member extending across said filling member and said anchor member, and a coupling member extending through said flanges, anchor member, and filling member, and said bumper member, substantially as described.
30. 26. A composite end sill for railway-cars, said sill comprising a plate metal channel member formed to present an upright back face and to present upper and lower horizontal flanges directed away from the car 35 frame, an anchor member placed between said flanges and secured to the upright web of the channel member with a link space between the anchor member and the upper flange, a filling member between the anchor 40 member and the lower flange, a metal bumper member extending across said anchor member and said filling member and the lower flange, and a coupling member extending through said flanges, anchor member, and filling member, and said bumper, substantially as described.
27. A composite end sill for railway-cars, said sill comprising a plate metal channel member formed to present an upright back 50 face and to present upper and lower horizontal flanges directed away from the car frame, a filling member between said flanges, bolts extending through said spaces, and spacing sleeves on said bolts, substantially as described.
55. 28. A composite end sill for railway-cars, said sill comprising a plate metal channel member formed to present an upright back face and to present upper and lower horizontal flanges directed away from the car 60 frame, a filling member located between and reaching outward beyond said flanges, bolts extending through said spaces, and spacing sleeves on said bolts, substantially as described.
29. A composite end sill for railway-cars, said sill comprising a plate metal channel member formed to present an upright back face and to present upper and lower horizontal flanges directed away from the car 70 frame, a wood filling member between said flanges, bolts extending through said spaces, and spacing sleeves on said bolts, substantially as described.
30. In a railway-car, the combination 75 with side sills, of a plate metal end sill member formed to present a continuous and upright back face and to present upper and lower horizontal flanges free from each other and extending from end to end of the 80 sill and directed away from the car frame, substantially as described.
31. In a railway-car, the combination with side sills, of a plate metal end sill member formed to present a continuous and 85 upright back face and to present upper and lower horizontal flanges free from each other and extending from end to end of the sill and directed away from the car frame, and a coupling bolt extending through said 90 flanges, substantially as described.
32. In a railway-car, the combination with side sills, of a plate metal end sill member formed to present an upright back 95 face and to present upper and lower horizontal flanges directed away from the car frame, and spacing means intervening said flanges, substantially as described.
33. A composite end sill for railway-cars, said sill comprising a plate metal channel 100 member formed to present an upright back face and to present upper and lower horizontal flanges directed away from the car frame, bolts extending through said flanges, and sleeves surrounding said bolts, substantially as described.
34. A composite end sill for railway-cars, said sill comprising a plate metal channel member formed to present an upright back 105 face and to present upper and lower horizontal flanges directed away from the car frame, and a filling member between said flanges, substantially as described.
35. In a railway-car, the combination of an end sill comprising a plate metal channel member formed to present a continuous and upright back face and to present upper and lower horizontal flanges free from each 115 other and extending from end to end of the sill and directed away from the car frame, and a frame member over-lapping and secured to the end sill at each end of the latter, substantially as described.
- In testimony whereof I have signed my name this 21st day of August, in the year 125 one thousand nine hundred and twenty three.

HUGH W. SANFORD.
